(57) **CLAIM**

The ornamental design for an enclosure for desktop power cord and cable management, as shown and described.

DESCRIPTION

FIG. 1 is a perspective view of an enclosure for desktop power cord and cable management, wherein the structures shown in broken lines form no part of the design;

FIG. 2 is a front elevation view of the enclosure for desktop power cord and cable management of FIG. 1, wherein the structures shown in broken lines form no part of the design;

FIG. 3 is a first side elevation view of the enclosure for desktop power cord and cable management of FIG. 1, wherein the structures shown in broken lines form no part of the design;

FIG. 4 is a second side elevation view of the enclosure for desktop power cord and cable management of FIG. 1, wherein the structures shown in broken lines form no part of the design;

FIG. 5 is a rear side elevation view of the enclosure for desktop power cord and cable management of FIG. 1;

FIG. 6 is a top plan view of the enclosure for desktop power cord and cable management of FIG. 1, wherein the structures shown in broken lines form no part of the design;

FIG. 7 is a bottom plan view of the enclosure for desktop power cord and cable management of FIG. 1; and,

FIG. 8 is a second perspective view of the enclosure for desktop power cord and cable management of FIG. 1 with a lid in the top side shown in an open position, wherein the structures shown in broken lines form no part of the design.
